PROCESS OF MANUFACTURING SMOKER'S ARTICLES

Louis J. Krensky and Samuel Gessler, Chicago,
Ill.; said Gessler assignor to said KrenskyNo Drawing. Application November 13, 1931
Serial No. 574,924

13 Claims. (Cl. 131—55)

The invention relates to smoking tobacco and has as an object the provision of a process of preparing tobacco for smoking particularly adaptable to the manufacture of cigars.

5 It is a further object of the invention to so treat tobacco as to improve its smoking qualities.

It is a further object of the invention to provide a process for manufacturing a cigar, cigarette or the like whereby its qualities of smoothness, taste, and odor are markedly improved.

10 It is a further object of the invention to provide a cigar comprising a novel combination of materials whereby its smoking qualities will be equal to the usual cigar made of tobacco of a better grade than that actually embodied in the product of the invention.

15 The fundamental principle of the invention is the combination of the materials of coffee with tobacco to be used for smoking purposes and the results secured are due to a combination of expedients for effecting the above result, the elements of which combination each has virtue in itself and when both are applied achieve 20 the full advantage of the invention. One of said elements is the combination of the coffee berry physically with the tobacco and the other element is the treatment of the tobacco by the vapors of a boiling coffee infusion.

25 In the preferred embodiment of the process the tobacco is first cased in a solution of ammonium carbonate, is then shaken out, packed in burlap, and allowed to cure for a period of substantially twelve hours. When applied to the manufacture of cigars the filler tobacco is treated in this manner. The cased material after curing is then shaken and aerated. The next step in the preferred embodiment of the invention is the 30 subjection of the material to the vapors of a boiling coffee infusion. For this purpose a receptacle is provided which is desirably equipped with a tight closure and a wire mesh rack standing above the level of the liquid therein. A coffee infusion is placed in the liquid containing portion of the boiler desirably of a strength corresponding with one-half gallon of water to one-half pound of finely ground coffee. This infusion is brought to the boiling point upon which the material cured as above described is placed upon the rack and the boiler closed. The boiling of the liquid is then continued desirably for a period of from six to twelve hours and the heat in the boiler is preferably raised to substantially 35 240° F.

40 After treatment by the resulting vapors of the

coffee infusion for the time indicated, heating is discontinued and the contents of the boiler are allowed to stand for an additional period of substantially eight hours whereby the vapors will have condensed within and upon the material. 60

The tobacco is then removed, thoroughly shaken, aerated, and packed tightly in burlap and allowed to lie for further curing for a period of about eight days. The thus cured tobacco is shaken, aerated and dusted with pulverized coffee. The amount of coffee thus combined with the tobacco depends entirely upon the taste. For manufacture of cigars the coffee dusted leaves are stripped, booked, and allowed to lie until in proper condition to be worked by the cigar maker. 70

75 The filler as above described is bunched with a binder cased in a solution of coffee flavoring extract. Desirably the wrapper which is subsequently applied to the cigar is also cased in the same manner, each being allowed to lie for substantially eight hours after casing to soften to a condition for use.

80 With the binder and filler prepared as above the binder is applied to the filler with an addition of comminuted coffee berry, desirably applied by sprinkling the binder with the coffee and wrapping the same about the filler. Only a small quantity of the dry coffee is necessary for each cigar.

85 The results secured by the invention are thus partially due to the treatment of the tobacco with the vapors of coffee and partially to the presence of the comminuted coffee berry. Advant- 90 ageous results may be had by use of either of these elements without the other.

In the manufacture of pipe or cigarette tobacco the material may be treated as above described with the mixture of the comminuted coffee in the mass thereof.

95 The coffee berry included with the tobacco when ready for use may be either raw or roasted, certain advantages inhering in each of these forms. Some aroma escapes when a raw berry is roasted. Hence when the raw berry is used, it will be gradually roasted and burned as the tobacco is consumed and greater aroma will be given off. On the other hand roasted berry pul- 100 verizes more readily than raw berry and good results have been secured with roasted com- minuted berry.

105 Minor changes may be made in the steps of the process or in the physical embodiment of the article without departing from the spirit of the invention within the scope of the appended 110 claims.

I claim:

1. The process of treating smoking tobacco which comprises subjecting the material to vapors given off by a boiling coffee infusion at a temperature substantially in excess of 212° F. 5
2. The process of treating smoking tobacco which comprises subjecting the material to vapors given off by a boiling coffee infusion at a temperature substantially in excess of 212° F. and 10 subsequently combining the thus treated material with comminuted coffee berry.
3. The process of treating smoking tobacco which comprises suspending the material over a boiling coffee infusion in a closed space for a period of hours, discontinuing heating and allowing the material to cool in the closed space, and removing and aerating the material. 15
4. The process of treating smoking tobacco which comprises casing the material by impregnating the same with a solution of ammonium carbonate and packing for fermentation, subjecting the thus treated material to vapors of a boiling coffee infusion. 20
5. The process of treating smoking tobacco which comprises casing the material by impregnating the same with a solution of ammonium carbonate and packing for fermentation, subjecting the thus treated material to vapors of a boiling coffee infusion and allowing the material 25 to cool in presence of said vapors whereby to condense the vapors within and upon the mass of the material.
6. The process of making a cigar, cigarette or the like which comprises subjecting filling material to vapors of a boiling coffee infusion, combining the thus prepared material with a small quantity of comminuted coffee berry and wrapping for use. 30
7. The process of making a cigar which comprises subjecting filler tobacco to the vapors of boiling coffee infusion, sprinkling comminuted coffee berry upon a binder of leaf tobacco, wrapping the binder and coffee about a bunch of the treated filler, and finally wrapping the bunch 35 of tobacco and coffee for use.
8. The process of making a cigar which comprises subjecting filler tobacco in a closed space under pressure to the action of vapors of coffee infusion boiling at a temperature in excess of 50 112° F., allowing the material to cool while said

space remains closed, forming a bunch of the thus treated filler by enclosure with a binder sprinkled with comminuted coffee berry and wrapping the thus formed bunch for use. 80

9. The process of making a cigar which comprises casing filler tobacco in ammonium carbonate solution, subjecting the thus treated filler to vapors of boiling coffee infusion under pressure, causing said vapors to condense in and upon the filler while cooling, packing the thus treated filler to cure for a period of days, forming the filler into a bunch comprising a small amount of comminuted coffee berry and wrapping the bunch for use. 85

10. The process of making a cigar which comprises treating filler tobacco with vapors of a boiling coffee infusion, casing binder tobacco leaf in a solution of extract of coffee, forming a bunch of the thus treated filler and binder and a small quantity of comminuted coffee berry and wrapping the bunch for use. 90

11. The process of making a cigar which comprises casing filler tobacco in a solution of ammonium carbonate and packing the same to cure, subjecting the cured material to the action of vapors of boiling coffee infusion, allowing said vapors to condense in and upon the material, aerating the material and again packing the same to cure, casing binder and wrapper leaf each in a solution containing extract of coffee combining the filler binder and wrapper to form the finished product. 100

12. The process of making a cigar which comprises casing filler tobacco in a solution comprising ammonium carbonate, closely packing the thus treated material in an air pervious covering to cure for a period of days, subjecting the cured filler to the action of vapors of a boiling coffee infusion for a period of hours in a closed space, allowing the material to cool in said space for a further period of hours, casing binder and wrapper leaf each in a solution containing extract of coffee, enclosing the filler in the binder carrying a sprinkling of comminuted coffee berry and enclosing the thus formed bunch in the wrapper. 110

13. In a process of curing tobacco the step of steaming the tobacco over a boiling coffee infusion for an extended period of time. 115
